United States Patent Office.

J. S. NICHOLSON, OF ANAMOSA, IOWA.

Letters Patent No. 82,341, dated September 22, 1868.

IMPROVED CLOTHES-PRESS.

The Schedule referred to in these Letters Patent and making part of the same.

TO ALL WHOM IT MAY CONCERN:

Be it known that I, J. S. NICHOLSON, of Anamosa, of the county of Jones, and State of Iowa, have invented a new and useful Clothes-Press; and I do hereby declare that the following is a full and exact description thereof, reference being had to the accompanying drawing, and to the letters of reference marked thereon.

The nature of my invention consists in keeping the clothes clean and free from dust; keeping them straight and free from wrinkles; keeping them in any room without occupying but a small space, as well as the ease and convenience of getting at them.

To enable others skilled in the art to make and use my invention, I will proceed to describe its construction and operation.

It consists of two frames, a front frame and a back frame. The back frame is represented in the drawing by the letter A, and is composed of two upright pieces, represented in the drawing by the figures 1 and 2, fastened together by a cross-piece, represented in the drawing by the figure 3. This piece is jointed into the upright strips below the top, so as to project in front; and at the bottom of this frame there is a board, represented in the drawing by the figure 4. It is fastened into the two upright pieces 1 and 2, projecting in front. The open space between these four pieces is covered with a piece of oil-cloth, represented in the drawing by the figure 5. The piece across the top, represented in the drawing by the figure 3, has hooks on the under side, to hang heavy clothing on; and on the right-hand upright piece an iron plate is fastened with screws; and on this plate there are three arms, represented by three letters, a, b, and c. The first arm is about three inches from the top piece 3, and the three arms are about three inches from each other, respectively. The first arm, represented by the letter a, is about three inches long; the second arm, represented by the letter b, is about seven inches long; and the third arm, represented by the letter c, is about eleven inches long. Each arm is composed of two iron bars, about one and one-half inch apart, with a hole in the outer end, admitting a bolt, represented by the letter d; and these bolts pass through the ends of three wooden bars, forming a hinge-joint at the end of each arm. These wooden bars are represented by three letters, e, f, and g, and reach across to the opposite side, and rest on iron rests. These rests are on an iron plate, fastened to the left-hand upright piece, 1, and this plate is represented in the drawing by the letter h. These wooden bars all swing parallel with each other. There is also a front frame, represented in the drawing by the letter B. This is made so as to cover the frame, represented by the letter A; and the top of this frame B fits over the top of this frame A; and the lower end of the two upright pieces in the second frame is fastened together by a strip of flat iron, represented by the letter i, bent to fit the outer edge of the board across the bottom of the first frame; and this second frame is fastened to the first by hinges, and it also has an oil-cloth covering, represented in the drawing by the letter j; and this keeps the clothing free from all dust, dirt, &c.

The press is fastened to the wall by screws passing through the four corners of the first frame, A.

What I claim as my invention, and desire to secure by Letters Patent, is—

In a clothes-press, the combination and arrangement of the frames A and B, uprights 1 and 2, cross-piece 3, shelf 4, the coverings 5 and j, the arms a, b, and c, the bars e, f, and g, and rest h, as and for the purpose specified.
